UNITED STATES PATENT OFFICE.

WILLIAM S. WRIGHT, OF NEWARK, OHIO, ASSIGNOR TO BESSIE B. WRIGHT, OF ANNAPOLIS, MARYLAND.

RAILWAY-CAR SEAT.

1,335,950.

Specification of Letters Patent.

Patented Apr. 6, 1920.

Application filed March 15, 1919. Serial No. 282,802.

To all whom it may concern:

Be it known that I, WILLIAM S. WRIGHT, a citizen of the United States of America, and resident of Newark, county of Licking, 5 and State of Ohio, have invented certain new and useful Improvements in Railway-Car Seats, of which the following is a specification.

This invention relates broadly to railway 10 car seats, and more particularly to a car seat of the reversible type.

The primary object of the invention is to simplify and structurally improve that type of reversible car seats in which the 15 seat back is shiftable from one lateral edge of the seat to the other, providing a structure in which the seat cushion is slightly moved in the opposite direction simultaneously with reversal of the seat back and is 20 slightly tilted, or has its angle of inclination changed in a manner conducive to the comfort of an occupant of the seat.

A further object is to provide a car seat in which the entire reversing mechanism is 25 located beneath the seat cushion rather than at the ends of the latter, thereby not only eliminating danger of injury to passengers, but also permitting of the use of the greatest possible length of seat cushion.

30 A still further object is to provide a seat reversing mechanism which is rendered peculiarly free from the shifting strains to which such seat structures are commonly subjected, by providing such a structure and 35 arrangement of parts that no direct or near center forces must be overcome in starting shifting movement. In other words, it is an object to provide a structure in which the tendency of shiftable parts to bind or lock, 40 retarding free shifting movement, is largely counteracted or overcome.

Another object is to provide a seat having such an end construction that twisting or misalignment of the seat frame is effectively prevented.

With these and other objects in view, the invention resides in the features of construction, arrangement of parts and combinations of elements which will hereinafter be 50 fully described, reference being had to the accompanying drawings, in which—

55 Figure 1 is a front elevation of one end of a seat embodying my invention, the seat back and seat cushion being shown in broken lines;

Fig. 2 is a transverse section on line 2—2, Fig. 1;

Fig. 3 is a section on line 3—3, Fig. 2;

Fig. 4 is an enlarged inner face view of 60 an end plate;

Fig. 5 is a transverse section of the same on line 5—5, Fig. 4;

Fig. 6 is an inner face view of one of the supports for the seat cushion;

Fig. 7 is a transverse section of the same 65 on line 7—7, Fig. 6;

Fig. 8 is an elevation of the rotatable shaft showing the levers carried thereby;

Fig. 9 is an end elevation of the same;

Fig. 10 is an inner face view of one of the 70 standards upon which the seat back is mounted; and—

Fig. 11 is an edge view of the same.

Referring to said drawings, in which like designating characters distinguish like parts 75 throughout the several views—

1 indicates a pedestal or leg constituting one of the supports upon which the seat and seat-shifting mechanism are mounted. Obviously, two such legs may be employed, or the seat may be mounted upon the car wall at one end and upon such a leg at the other. Mounted upon the legs 1, or upon a leg at 80 one end and the car wall at the other, according as one or two legs are employed, 85 are two longitudinally extending frame members 2, preferably composed of angle-iron, as shown; and rigidly secured, as by bolts 3, to each of the opposite ends of said members 2 is an inwardly directed flange 4 90 formed on the lower edge of an end plate 5 which is herein shown as rectangular in form and composed of pressed steel with in-turned top and end flanges 5a. Rigidly carried on the inner face of each end plate 95 is a channel member 6 the channel of which is arcuately curved and constitutes a trackway in which are received rollers 7 that are rotatably mounted on the outer face of the head portion 8a of a metal standard 8 upon 100 which an end of the seat back 9 is mounted. Said rollers 7 support said seat back and are designed to travel along said trackway as said back is shifted from one of its operative positions to the other.

105 Mounted upon the inner face of each end plate 5 beneath the trackway 6 and at a point approximately midway between the ends of said plate is a socket member 10 in which is rotatably mounted one end of a 110

shaft 11 which extends throughout the length of the seat.

The head portion 8^a of each standard 8 is formed with an inwardly facing channel 12 therein, said channel being herein depicted as of inverted-V shape, but it may be of arcuately curved form instead. Received in and adapted to travel along said channel 12 is an outwardly extending stud or pin 13 carried by a lever arm 14 which is rigidly mounted upon the shaft 11. Said arm is prolonged somewhat beyond the location of the pin 13 so that when the seat back is being shifted the prolonged, or free, end 15 of the arm will, as said back approaches the center of travel or movement, enter a pocket 15 of semi-circular form provided in an outwardly projecting lip 16 which is formed on the head portion 8^a of the standard 8 directly over the apex of the channel 12. The engagement of the end of said arm in said pocket results in the pin 13 being carried over the apex of the lower wall of the channel 12 without lost motion and without 25 a dead point or dead center being encountered.

Seated and transversely slidable upon the frame members 2 adjacent to each end of the seat frame are the lower relatively-inclined inwardly-flanged edges of a pressed steel seat-cushion support 17 having lugs or posts 18 on its upper edge adapted to engage, as ordinarily, with the seat cushion 19. Provided in said support 17 midway between the ends of the latter is a T-shaped slot in the horizontal head portion 20 of which is received the shaft 11, said shaft being disposed at one or the other end of said portion 20 of the slot according as the seat cushion 19 occupies one or the other of its operative positions, as will hereinafter be explained. Said shaft 11 carries thereon at a point adjacent to and outward with respect to the position of the support 17 a lever arm 21 having an inwardly directed stud or pin 22 which is movably disposed in the vertical stem portion 23 of the T-shaped slot in said support.

In practice, slight force applied by hand 50 to the seat back 9 accomplishes reversal of the positions of said back and the seat cushion 19. Force so applied causes said back to swing from one limit of its movement to the other, the rollers 7 traveling 55 forward from one end of the trackway in the channel member 6 to the other. As the standard 8 which carries said rollers moves forward, the lever arms 14 and the shaft 11 are rotated forward. When the prolonged ends of said arms enter the pockets 15, being guided into the latter through travel of the pins 13 in the inverted V-shaped channel 12, the rotation of said shaft is accelerated to the extent that the movement 60 of the back is continued to its reversed

position and the pins 13 carried over the apex of the channel with the application of but slight force and without lost motion.

Due to the fact that the pins 13 of levers 14 occupy positions under, or on a lower plane than, the foremost rollers 7 at the commencement of reversing movement, the reversing force applied to the top and end of the seat back 9 and transmitted to said levers tends to lift up the foremost roller 75 at the opposite end of the back and thus to prevent the tendency of the rollers to lock in the channel of the member 6. In other words, the arrangement of the levers 14 with portions disposed in the trackway 80 12 serves to remove all tendency on the part of the seat-back-supporting rollers to bind or lock. This feature will be clearly understood when it is pointed out that, in the absence of the levers 14, reversing force 85 applied to the top of the seat back would cause the forward roller to be forced down against the lower flange of the channel member 6 and the rear roller to be forced up against the upper flange of said member, 90 resulting in binding or locking of the inter-engaged parts. As stated, this tendency to lock or bind is effectually counteracted through the upward movement of the levers 14 to the extent that the foremost rollers 7 95 are lifted off the lower flange.

As is obvious, the mechanism facilitates and provides for accelerated movement through the shaft from one end of the seat back to the other when reversing force is 100 applied to the seat back.

Due to the fact that the opposite arms 14 occupy correspondingly inclined positions on opposite ends of the shaft, and the pins 13 thereof operate in corresponding 105 channels, it is apparent that the opposite ends of the seat back will move uniformly and without any twisting strains which would be due to one end traveling in advance of the other.

As the shaft 11 rotates, actuated by the arms 14 in engagement with the heads 8^a of the standards, force is exerted through the pins 22 and the arms 21 by which said pins are carried whereby the seat-cushion supports 17 are actuated to slide transversely upon the frame members 2 in a direction opposite to that in which the seat back is being moved. In other words, a leverage is exerted through the arms 21 of the rotating shaft 11 which shifts the supports 17 and the seat cushion 19 carried by the latter to a reversely inclined position corresponding with that required by the reversal of the position of 120 the seat back. Further, as is obvious, the seat cushion is firmly held against tilting by reason of the fact that in either of the operative positions thereof, the shaft 11 occupies a seated position with respect to an 125 130

end of the horizontal head portion 20 of the T-shaped slot in each cushion support 17.

It will be noted that the mechanism described is extremely simple and provides for reversal of the seat without binding or locking of interengaging parts and without subjecting any of said parts to twisting, movement-retarding, or other undue strains.

10 What is claimed is:—

1. In a car seat, the combination with a seat cushion and shiftable supports therefor, of seat shifting mechanism including a rotatable shaft, a shiftable seat-back supporting standard, said standard having a guideway in its lower end and having a pocket located over and intermediate the ends of said guideway, and arms carried by said shaft, said arms having portions disposed to travel 15 in said guideway and having other portions adapted to enter said pockets for interengaging said arms and said standards in such manner that rotation is imparted to said shaft during shifting movement of said 20 standards.

2. A supporting standard for reversible seat backs having an arch-like guideway in a face thereof and provided with a downwardly opening pocket at a point above and 25 midway between the ends of said guideway.

3. A supporting standard for reversible seat backs having an inverted V-shaped guideway formed therein adjacent to its lower end and provided with a downwardly 30 opening pocket at a point over the apex of said guideway.

4. In a car seat, the combination with seat cushion supports, of mechanism for shifting the positions of said supports including a 40 rotatable shaft having arms engaged with said supports, a pair of seat-back-supporting standards each having a curved guideway formed therein adjacent to its lower end and provided with a downwardly opening pocket 45 at a point over the middle portion of said guideway, and lever arms carried by said shaft having pins disposed for travel in said guideway and having their ends prolonged beyond said pins for seating in said pockets.

5. In a car seat, the combination with seat-cushion supports, of mechanism for shifting the positions of said supports including a rotatable shaft having arms engaged with said supports, a pair of seat-back-supporting 55 standards each having an inverted V-shaped guideway formed therein adjacent to its lower end and provided with a downwardly opening pocket at a point over the apex of said guideway, lever arms carried by said 60 shaft having pins disposed for travel in said guideway and having their ends prolonged beyond said pins for seating in said pockets, end plates upon which said shaft is mounted, said plates having curved inwardly facing 65 guideways thereon, and rollers carried by

said standards mounted for travel in the last-mentioned guideways.

6. In a reversible car seat, the combination of a frame, end plates supported by said frame, curved tracks supported by said plates, seat-cushion supports shiftable transversely upon said frame, a back movable over said seat for reversing its position, standards supporting said back and having corresponding inverted V-shaped guideways 75 adjacent to the lower ends thereof and also provided with a downwardly opening socket over the apex of said guideway, rollers carried by said standards mounted to travel on said curved tracks, a shaft having its opposite ends rotatably mounted on said end plates, a pair of lever arms carried by said shaft, laterally directed pins carried intermediate the ends of said arms and disposed to travel in said guideways, the free ends of 80 said arms being adapted to seat in said pockets during a part of the reversing movement of said standards whereby rotation is imparted to said shaft, said seat-cushion supports having T-shaped slots therein and said 85 shaft being adapted to seat at one or the other end of the head portion of said slot according to the operative position occupied by said supports, and a second pair of lever arms carried by said shaft and having pins 90 movably disposed in the stem portion of said slot.

7. A car seat comprising a seat cushion and a seat back, the latter having carrying rollers and being shiftable over the former to 100 a reversed position, and mechanism intermediate said back and said cushion whereby a reversing force applied to one end of said back is transmitted to the opposite ends of the seat for producing uniform relative 105 movements of said parts, said mechanism including means for counteracting all tendency of said rollers to bind, whereby the parts are freed from twisting or binding strains.

8. In a car seat, the combination with a seat back, of shiftable standards supporting said back, said standards having curved guideways in their lower ends, rigidly supported end plates having curved inwardly facing guideways thereon, a pair of rollers 110 carried by each standard and disposed for travel in the last-mentioned guideways, a rock-shaft having its ends mounted in said end plates, and lever arms carried by said shaft and having parts slidably disposed in 115 the guideways of said standards in such relation to said rollers that locking or binding of the latter upon the application of reversing force to said standards is counteracted.

9. In a railway car seat, the combination with a seat frame and a cushion shiftable thereon, of a reversible seat back, supporting standards rigidly attached to said back and having transverse channels in their lower ends, and mechanism having parts disposed 125

65 130

for travel in and adapted to be actuated through their engagement with said channels whereby said cushion is shifted simultaneously with reversal of said back, said mechanism being located in its entirety below the plane of the bottom of said cushion to permit the latter to occupy the full width of the space between said standards and also in a position wherein no part thereof is presented above said plane during

shifting movement, said mechanism being also disposed to leave substantially vacant the space below said seat frame.

In testimony whereof, I affix my signature in presence of two subscribing witnesses.
